UNITED STATES PATENT OFFICE.

HERMANN LEMP, OF LYNN, MASSACHUSETTS, ASSIGNEE TO GENERAL ELECTRIC COMPANY, A CORPORATION OF NEW YORK.

SUPPLYING FUEL AND WATER TO BOILERS.

1,041,640.

Specification of Letters Patent. Patented Oct. 15, 1912.

Application filed August 16, 1907. Serial No. 388,752.

To all whom it may concern:

Be it known that I, HERMANN LEMP, a citizen of the United States, residing at Lynn, county of Essex, State of Massachusetts, have invented certain new and useful Improvements in Supplying Fuel and Water to Boilers, of which the following is a specification.

This invention relates to that class of steam generators known as semiflash boilers, and its object is to regulate automatically the supply of fuel and water in order that the steam pressure may be kept at or near a constant value. The fuel ordinarily used is a liquid hydrocarbon, and this and the feed water are usually supplied to the burner and the boiler respectively by means of pumps. Sometimes pneumatic pressure is employed instead of a pump to force the liquid fuel from its reservoir to the burner. It is necessary to use great care in regulating the supplies of fuel and water to prevent overheating on the one hand and excessive cooling on the other, in order to maintain a normal steam pressure and meet the varying demands upon the boiler. There are two factors which are customarily depended upon to effect an automatic control of the fuel and water. These are the pressure and the temperature of the steam. In the present case, I make use of both, the fuel supply being controlled by both, and the water supply by the pressure only. Briefly stated, the oil or other liquid fuel can feed by gravity to the burners, although the main supply is forced from a reservoir under pneumatic pressure. The flow is governed by a regulator actuated by elastic fluid under pressure, preferably compressed air, which is controlled by a self-closing valve normally held shut by the pressure of the air. A movable abutment responsive to an excessive steam pressure in the boiler acts to open said valve and admit the air to the fuel-controlling valve. The air can also flow through a branch pipe to a movable abutment arranged to shut off the flow of steam to a steam pump which supplies the boiler with water. As an additional safeguard, a thermostatic air-valve is provided in a shunt around the steam-pressure-controlled air-valve, so constructed that upon

an abnormal rise in the temperature of the steam the fuel-controlling valve will be closed. The air pressure in the fuel tank is so calculated in proportion to the size of the burners that when the fuel-controlling valve is wide open the burners will evaporate the maximum quantity of water which the boiler is designed to take care of. The water pump, moreover, is provided with a speed-regulating device which, when the steam admission valve is wide open, allows it to supply no more water to the boiler than the burners can evaporate. In other words, the ratio between the quantities of fuel and water supplied to the boiler is such as to enable the boiler to furnish its maximum output of steam at the proper temperature for an indefinite period. An excessive steam pressure cuts off both fuel and water, and both are turned on again when the pressure drops to normal. In the contingency of the water tank becoming empty the increased temperature of the steam operates through the thermostat to shut off the fuel.

The accompanying drawing is a diagram of parts and connections illustrating my invention.

The boiler is conventionally represented as a zigzag coil of pipe 1, inclosed in a casing 2, lined with heat-resisting and insulating material. The casing extends below the coil to form a fire chamber in which are burners 3 adapted to vaporize the liquid fuel. A fuel tank 4 is located above the level of said burners, so that fuel will flow to them by gravity through the pipe 5, and maintain a pilot light when the main supply is shut off. The main fuel reservoir 6 is connected with the pipe 5 by the pipe 7. The fuel in said reservoir is under air pressure of say 80 pounds to the square inch. A check-valve 8 prevents this air pressure from forcing fuel back into the tank 4.

The pipe 7 is controlled by a pressure-actuated regulator comprising a valve 9 connected to a movable abutment 10 which is exposed to the action of compressed air in a pipe 11 leading from a suitable source of supply, such as the tank 12. The flow of air in this pipe is controlled by a valve 13 which is held normally shut by the pres-

sure of the air in the tank 12. The valve can be opened by a multiplying lever 14 receiving motion from an abutment, such as the diaphragm 15, which is exposed on one side to the pressure of the steam conveyed to said diaphragm by a pipe 16, which branches from the steam main 17. The spring 18 on the opposite side of said diaphragm is set to yield at the maximum steam pressure permissible. The multiplying lever 14 gives a very delicate and close regulation for slight changes in pressure.

The steam pump for supplying water to the upper end of the boiler comprises a steam cylinder 19 and a water cylinder 20, the latter drawing water from a tank 21 through the pipe 22. The steam end of the pump receives steam through a pipe 23 connected to the main 17. Interposed in the pipe 23 is a shut-off valve 24 working in a casing 25 and attached to a movable abutment, such as a piston 26, to the underside of which compressed air is led through a pipe 27 branching from the pipe 11, and controlled, therefore, by the valve 13. It follows that when an abnormal rise in steam pressure opens said valve 13, the air not only shuts the fuel-controlling valve 9, but also shuts off the steam from the pump and thereby stops the water supply. A balanced throttle valve 28 regulates the admission of steam to the pump, and said throttle is controlled by a speed regulator 29, preferably of the Mason type, whose weighted lever 30 is connected with said throttle by a rod 31. So long as the shut-off valve 24 remains open, the regulator 29 maintains the speed of the pump constant, irrespective of variations in steam pressure or load. The quantity of water supplied to the boiler in any given time is thus kept constant, and by a proper adjustment of the regulator this can be fixed at just the right amount for the burners to evaporate when working under normal tank pressure.

It may happen that, for some reason, such as the failure of the water supply, the steam rapidly rises in temperature, and this might occur without any rise in pressure, if the main throttle valve 32 was open. In order to prevent burning out the boiler in such an event, I provide a shunt around the valve 13 from the air tank 12 to the fuel-controlling valve 9, comprising a pipe 33 running from said tank to the pipe 11 at the point 34, between the valve 13 and the valve-diaphragm 10. This shunt air-pipe 33 is controlled by a valve 35 which is held normally closed by the air pressure. It can be opened, however, by a thermostat exposed to the live steam and responsive to a dangerous rise in the temperature thereof. The opening of said valve admits air to the pipe 11 and operates to shut off the fuel

at the valve 9. A check valve 36 prevents the air from entering the pipe 27 and operating the steam shut-off valve 24, as it is desirable to keep up the water feed in order to cool off the boiler. If the water has given out, no harm will result from not closing the valve 24, as the pump will soon stop owing to the failure of steam. The thermostat which operates the valve 35 is preferably composed of a section 37 of the steam main, said section being made of a metal having a large coefficient of expansion, such as brass or copper. Near one end of said section is an arm 38 to which is secured one end of a rod 39 which is made of a material, such as nickel-steel, having a lower coefficient of expansion than the section 37 of the steam main. Near the opposite end of the section 37 is secured a bracket 40 on which is mounted the casing of the valve 35. Pivoted on this bracket is a lever 41 to which the other end of the rod 39 is pivotally attached. The free end of the lever is arranged to open the valve 35 when the section 37 becomes relatively longer than the rod 39 owing to the greater expansion of said section by an increase in temperature of the steam flowing through it. When the temperature falls, the section 37 contracts and shortens more than the rod 39, so that the lever is moved away from the valve 35 and it is permitted to close.

The valve is held normally closed by the pressure of the air in the tank 12. When the valve is opened by the thermostat in the manner above described, the air passes freely to and operates the pressure regulator valve 9, thereby closing the pipe 7 and shutting off the main fuel supply. The fire is thus subdued and the abnormal superheating of the steam is checked, so that its temperature can fall to a safe value.

It will be observed that the thermostatic section 37 of the steam main is located between the boiler and the pipe 23, feeding steam to the pump, so that live steam is constantly flowing through said thermostatic section even when the main throttle 32 is closed.

The normal conditions of operation, therefore, are a predetermined ratio of fuel and water supply in quantities sufficient to enable the boiler to produce its maximum output, and the control of both fuel and water simultaneously by the pressure of the steam; with a thermostatic control of the fuel as a safeguard against overheating the boiler.

In accordance with the provisions of the patent statutes, I have described the principle of operation of my invention, together with the apparatus which I now consider to represent the best embodiment thereof; but I desire to have it understood that the

apparatus shown is only illustrative, and that the invention can be carried out by other means.

What I claim as new and desire to secure by Letters Patent of the United States, is,

1. In combination, a vapor generator, a burner for heating the fluid in the generator, means for supplying fluid to the generator, a controller for the fluid supply, means for supplying fuel to the burner, a controller for the fuel supply, a source of compressed air supply, and a regulator responsive to variations in the pressure in the generator for regulating the supply of compressed air from said source to said controllers to cause the latter to vary the supply of fluid and fuel to the generator and burner respectively.
2. The combination with a boiler, of a burner therefor, a source of liquid fuel supply, a pressure actuated regulator controlling the flow of said fuel to the burner, a steam pump for supplying water to said boiler, a pressure actuated regulator controlling the supply of steam to said pump, and means responsive to the boiler pressure for controlling both of said regulators.
3. The combination with a boiler, of a burner therefor, a source of liquid fuel supply, a pressure actuated regulator controlling the flow of said fuel to the burner, a steam pump for supplying water to said boiler, a pressure actuated regulator controlling the supply of steam to said pump, a source of elastic fluid pressure, and means responsive to the boiler pressure for admitting elastic fluid pressure to both of said regulators.
4. The combination with a boiler, of a burner therefor, a source of liquid fuel supply, a pressure actuated regulator controlling the flow of said fuel to the burner, a source of elastic fluid pressure, a means responsive to the temperature of the steam for admitting said elastic fluid pressure to the regulator and means responsive to the pressure of the steam for also admitting said elastic fluid pressure to said regulator.
5. The combination with a boiler, of a burner therefor, a source of liquid fuel supply, a pressure actuated regulator controlling the flow of fuel to the burner, a source of elastic fluid pressure, a valve controlling the admission of said elastic fluid pressure to the regulator, a thermostat exposed to the steam and arranged to operate said valve, and a valve controlled by the pressure of the steam for also admitting said elastic fluid pressure to said regulator.
6. A system of fuel and water supply for a boiler, comprising reservoirs for fuel and water, a steam water pump, a compressed air tank, a pressure actuated regulator controlling the flow of fuel, a second pressure

actuated regulator controlling the flow of steam to the pump, a third pressure actuated regulator connected with the steam main and controlling the admission of air to the other two regulators, a thermostat exposed to the steam between the boiler and the pump, and a valve controlled by said thermostat and admitting air to the fuel supply regulator.

7. A system of fuel and water supply for a boiler, comprising means for supplying the right quantity of water to be evaporated by a predetermined quantity of fuel into steam of a given temperature, means for supplying said fuel, a source of elastic fluid under pressure, pressure actuated devices for controlling both the fuel and the water supplies, and means responsive to the steam pressure which controls the application of elastic fluid from said source to said devices to simultaneously stop or start both supplies.

8. A system of fuel and water supply for a boiler, comprising means for supplying the right quantity of water to be evaporated by a predetermined quantity of fuel into steam of a given temperature, means for supplying said fuel, a source of elastic fluid under pressure, pressure actuated devices for controlling both the fuel and the water supplies, means responsive to the steam pressure which controls the application of elastic fluid from said source to the devices to simultaneously stop or start both supplies, and means responsive to an excessive temperature of the steam for shutting off the fuel.

9. In an apparatus of the character described, the combination with a vapor generator, of a fluid feed, a fuel feed, both of said feeds being controlled from a source of compressed air supply, and a regulator for controlling said air supply, said regulator being actuated by variations in pressure in the generator.

10. The combination with a boiler, of a burner therefor, a source of liquid fuel supply, a pump for supplying water to said boiler, a source of elastic fluid under pressure, and means actuated by said pressure fluid for simultaneously shutting off the fuel and water supply when the boiler pressure becomes excessive.

11. The combination with a boiler, of a burner therefor, a source of liquid fuel supply, a pump for supplying water, a source of elastic fluid pressure, valves adapted to be actuated by said pressure for controlling said fuel and water supplies, and means responsive to excessive steam pressure for admitting the fluid pressure to actuate said valves.

12. In apparatus of the class described, the combination of a generator; heating means coöperative therewith; means for regulating the supply of liquid to said gen-

erator and of fuel to said heating means, respectively; fluid-pressure actuated means for operating each of said regulating means; a thermostatic device in connection with said 5 generator for controlling the supply of fluid for operating the fuel-supply regulating means; and a device affected by the pressure in said generator for controlling the supply

of fluid to the liquid-supply regulating means.

In witness whereof, I have hereunto set my hand this twelfth day of August, 1907.

HERMANN LEMP.
